UNITED STATES PATENT OFFICE.

MILLARD J. ROBERTS, OF TONAWANDA, NEW YORK.

GAS BURNER.

Application filed February 1, 1926. Serial No. 85,307.

This invention relates to burners for consuming a mixture of air and gas and provides a burner having independent chambers, the mixture of air and gas being supplied to one of the chambers, designated as the primary chamber, the other chamber, designated as the secondary chamber, receiving air in regulated quantity and provided with outlets to which the gaseous mixture from the primary chamber is delivered by burner tubes, the mixture and air from the two chambers combining and mixing at the outlets of the secondary chamber to produce an intense heat when consumed.

While the drawings illustrate a preferred embodiment of the invention it is to be understood that in adapting the means to meet specific needs and requirements the design may be varied and such other changes in the minor details of construction may be resorted to within the scope of the invention as claimed without departing from the spirit thereof.

For a full understanding of the invention and the merits thereof, reference is to be had to the following description and the drawings hereto attached, in which,—

Figure 1 is a top plan view of a gas burner embodying the invention,

Figure 2 is a front view of the burner, partly in section and with parts broken away.

Corresponding and like parts are referred to in the following description and designated in both views of the drawings by like reference characters.

The burner may be of any outline, depending upon its particular application, the essential feature resulting in the provision of a primary chamber for reception of the gaseous mixture and a secondary chamber adapted to receive air for combining with the gaseous mixture at the flame outlet. As shown in the accompanying drawings, the burner is of circular outline, but as stated, the configuration is nonessential. For convenience the burner is formed in sections which are assembled and bolted, or otherwise secured. This enables the burner to be readily cast.

The numeral 1 designates the body of the burner which is provided with outlets 2 disposed by preference, at the upper, outer side. A partition 3 subdivides the interior of the burner into chambers 4 and 5, the chamber 4 being adapted to receive the gas-

eous mixture and is designated as the primary chamber. The chamber 5, designated as the secondary chamber is adapted to be supplied with air which is added to and commingles with the gaseous mixture at the outlets 2. Burner tubes 6 are set into the partition 3 and communicate with the primary chamber 4 and terminate within, or adjacent the outlets 2, so as to insure air from the secondary chamber 5 commingling with the gaseous mixture escaping from the outer ends of the burner tubes 6. The gaseous mixture may be supplied to the primary chamber 4 in any determined way and, as shown, a gas pipe 7 has outlets opening into mixing tubes 8 which are in communication with the primary chamber 4, preferably at opposite points, as indicated most clearly in both views of the drawings. An air pipe 9 connects with the burner at opposite points to equalize the supply of air thereto, and this pipe has a branch 10 which receives air in regulated quantity through the instrumentality of a damper 11 associated therewith.

The gaseous fuel from a suitable source of supply is delivered to the tube 8 and is mixed with air, the gaseous mixture passing from the mixing tube into the primary chamber 4, and from the latter through the burner tubes 6 and through the outlets 2 of the burner. Air, being supplied to the pipe 9 in regulated quantity, enters the secondary chamber 5 and passes therefrom through the outlets 2, mixing with the gas discharging at the outer end of the burner tubes 6. When the gaseous mixture is ignited the flame is intensified by the air escaping through the outlets 2 and since this secondary supply of air is restricted there is no loss of heat, as is experienced where the secondary supply of air is not controlled. When the secondary air supply is not controlled, an excess results, thereby lowering the efficiency of the burner, but in the present instance this objection is overcome by controlling the secondary air supply to the amount required for perfect combustion, thereby preventing the cooling of the surface of the burner, as is the case when the secondary air supply is uncontrolled and in the open.

Having thus described the invention, I claim:

1. An annular gas burner provided with outlets in the upper portion of its outer side,

- a partition dividing the burner into an inner gas chamber and an outer air chamber, tubes supported in the partition and radiating therefrom and extending across the air chamber and terminating within the outlets, means for supplying gas to the inner chamber at different points and means for supplying air at different points to the outer chamber.
- 10 2. An annular gas burner comprising similar sections and provided in the upper portion of its outer side with outlets, a flared

partition dividing the burner into an inner annular gas chamber and an outer annular air chamber, burner tubes carried by the 15 partition and radiating therefrom and extending across the air chamber and terminating within the outlets, means for supplying gas to the inner chambers of the sections and means for supplying air to the outer 20 chambers of the sections.

In testimony whereof I affix my signature.

MILLARD J. ROBERTS. [L.S.]
